UNITED STATES PATENT OFFICE.

FREDERIC S. CONVERSE, OF LYONS, NEW YORK.

COAL OR WOOD BAG.

SPECIFICATION forming part of Letters Patent No. 733,542, dated July 14, 1903.

Application filed July 14, 1902. Serial No. 115,481. (No model.)

To all whom it may concern:

Be it known that I, FREDERIC S. CONVERSE, a citizen of the United States, residing at Lyons, in the county of Wayne and State of New York, have invented certain new and useful Improvements in Coal or Wood Bags, of which the following is a specification.

This invention relates to packing and storing vessels, and more especially to those of flexible materials, such as bags, for containing coal or other heavy granular substance; and the object of the same is to construct a very strong bag, preferably of canvas, properly reinforced and provided with the necessary handles.

To this end the invention consists in the details of construction of both the bag and the handles therefor, all as hereinafter more fully described, and shown in the drawings, wherein—

Figure I is a perspective view of this bag complete. Fig. II is a bottom plan view. Fig. III is a vertical section. Fig. IV is a plan view of the blank from which the bottom is made. Fig. V is a detail of one of the main handles before its application to the bag.

Referring to the drawings, 1 designates the body of this bag, which is a piece of stout canvas or the like cut initially in rectangular shape and bent finally into cylindrical shape, as seen in Fig. I, its ends being connected with each other by riveting or stitching, or both, as at 2. The upper edge of this body is turned over a rope or similar device and sewed to the body on the outside, as at 3, thereby stiffening the edge, so that the mouth of the bag will stand open for the reception of its contents.

The bottom 5 of this bag is initially cut in the shape of a cross, as seen in Fig. IV. Then its four ends have their flaps 50 turned in on the dotted lines, after which the ends are folded upward and riveted or stitched along their edges to each other, as seen at 6, and finally the upper edge of the rectangular bottom piece thus formed is stitched or riveted, as at 7, to the lower end of the cylindrical body-piece 1, thereby producing a bag which when filled has a body approximately round and a base approximately rectangular, especially at its bottom and about one-third of the entire height of the bag, one which will

as a whole stand up alone. Reinforcing corner-pieces 10 of about the shape shown are stitched or riveted over the corners of the bottom piece, as seen in Fig. I, and these take up the wear and form feet on which the bag may stand. I preferably provide four handles. Two of these, which I call the "auxiliary" handles and have numbered 12, are riveted or stitched into the seam 7 and form handles by which the bag is usually shifted or dumped. The other two, which I call the "main" handles, diverge from their hand portions 13 downward into long arms 14, which are stitched or riveted throughout their length to the sides of the body 1, and preferably into the seam 7, and also downward in short arms 15, which pass into the mouth of the bag and stitched or riveted therein. The blank from which these handles are formed is best seen in Fig. V. It consists of double thicknesses 14 and 14' for the longer arms, between which is located the stiffener 16, as of wire, and these thicknesses are stitched together along their edges. It also consists of a shorter and wider piece 15, stitched along its edges for a short distance, as at 17, to that face of the longer arms which is to be downward in the finished handle. In making the latter the parts are assembled as above described and as shown in Fig. V, the whole given quarter-twists in opposite directions at the ends of what is to form the handpiece 13, (which is curved upward slightly, as shown,) the handle placed in position, and the longer and shorter arms stitched or riveted to the outer and inner sides of the bag, respectively. The stiffener being thus held into place not only stiffens the handle proper, as above described, but also strengthens the arms thereof, and hence stiffens the bag, whereby the use of this stiffened handle with a flexible bag possesses peculiar advantages. The shape of the arms of these handles assists in supporting the bag in upright position, and yet prevents tearing out in case the device is lifted when it is full of heavy substance, as coal.

It will be obvious that when not in use this bag can be folded on a vertical sectional line between the handles, and in its folded condition it can be packed in extremely small space. At all times it will occupy very little space, will retain little or no moisture and

will dry quickly, will wear longer than many bags now on market, and is cheap in construction and durable in use. The shape of the finished bag is such that it will not only stand alone whether full or empty, but it can be stacked by reason of the fact that the bottom is smaller than the body. Said bottom and its feet will probably wear first and can readily be replaced at slight expense.

10 The position and shape of the handles and the manner of their attachment greatly stiffen the bag and add to its life. If cloth of sufficient weight is used, one thickness thereof would answer, save possibly in the case of the handles.

15 It will be clear that either riveting or stitching could be used in most, if not all, the parts in this device, and hence where one is mentioned I desire to include the other.

What is claimed as new is—

20 1. A bag of flexible material comprising a body and a bottom secured at its upper edge to the body, the bottom being of lesser dimensions in contour than the body, the body taking a cylindrical shape and the bottom a square shape when the bag is filled, for the purpose set forth.

25 2. A bag comprising a body, a bottom cut initially into the shape of a cross with its four ends turned upward and stitched together along their meeting edges, the then upper edges of these ends being stitched to the lower edge of said body, and feet over the corners of the bottom, the body taking a cylindrical shape and the bottom a square shape when 35 the bag is filled.

30 3. A bag comprising a substantially cylindrical body, a bottom cut initially into the shape of a cross with its four ends turned upward and stitched together along their meeting edges, the then upper edges of these ends being stitched to the lower edge of said body, and feet comprising flexible corner-pieces stitched over the corners of said bottom, for the purpose set forth.

45 4. A bag comprising a body portion, and a bottom portion stitched to the lower end of the body portion; combined with auxiliary handles stitched into the seam between these two portions, and main handles with their 50 arms also stitched into said seam and stitched to the body portion and their handpieces rising above the upper edge of the latter.

55 5. A bag comprising a body portion, and a bottom portion stitched to the lower end of the body portion; combined with main handles whose arms diverge downward from their handpieces and are stitched to the exterior of the body portion and at their lower extremities into the seam between the body and bottom, and auxiliary handles stitched into said seam only.

60 6. A bag comprising a body portion, and a bottom portion stitched to the body portion; combined with main handles having stiffened handpieces rising above the upper edge of the body portion, these handles having arms depending from their handpieces and stitched

upon the exterior of the body portion and into the seam between this portion and the bottom, said main handles also having other arms depending from said handpieces and sewed to the inner face of the body, and auxiliary handles stitched into said seam only.

7. A bag comprising a body, and a bottom cut initially into the shape of a cross with its four ends turned upward and stitched together along their meeting edges, the then upper edges of these ends being stitched to the lower edge of said body.

8. As a new article of manufacture, a handle for flexible bags and the like consisting of a fabric strip in two thicknesses having arms at its extremities adapted to be stitched to the body of the bag, a stiffening-piece inserted between said thicknesses, and a third and wider thickness stitched beneath said other thicknesses opposite the stiffening-pieces, as and for the purpose set forth.

9. As a new article of manufacture, a handle for flexible bags and the like, the same consisting of a long fabric strip in two thicknesses connected along their edges and adapted to be stitched to the bag except at the center of their length, a stiffener between such thicknesses, and a short piece constituting a third thickness stitched to the lower side of the combined longer strips at their center and adapted to be stitched at its ends to the bag.

10. As a new article of manufacture, a handle for flexible bags and the like, the same consisting of a long fabric strip in two thicknesses connected along their edges and adapted to be stitched to the bag, a stiffener between such thicknesses, and a short piece stitched for a portion of its length to the longer strips and having unstitched arms at its extremities adapted to be stitched to the bag.

11. As a new article of manufacture, a handle for flexible bags and the like, the same consisting of a long fabric strip in two thicknesses connected along their edges and adapted to be stitched to the exterior of the bag, a stiffener between such thicknesses, and a short piece stitched for a portion of its length to the longer strips and having unstitched arms at its extremities adapted to be stitched to the interior of the bag.

12. As a new article of manufacture, a handle for flexible bags and the like, the same consisting of a long fabric strip in two thicknesses connected along their edges and adapted to be stitched to the bag, a stiffener between such thicknesses, and a short piece stitched for a portion of its length to the longer strips and having unstitched arms at its extremities adapted to be stitched to the bag, the combined elements being given quarter-twists near the ends of said stitch-lines so as to produce handpieces between the twists, and said handpieces being curved upward.

13. As a new article of manufacture, a handle for flexible bags and the like, the same

consisting of a long fabric strip in two thicknesses connected along their edges and adapted to be stitched to the exterior of the bag, a stiffener between such thicknesses, and a short

5 piece stitched for a portion of its length to the longer strips and having unstitched arms at its extremities adapted to be stitched to the interior of the bag, the combined elements being given quarter-twists near the ends of

said stitch-line so as to produce handpieces to between the twists.

In testimony whereof I have affixed my signature in presence of two witnesses.
